UNITED STATES PATENT OFFICE

ARTHUR C. KOOTZ, OF MILWAUKEE, WISCONSIN, ASSIGNOR TO THE GEM HAMMOCK & FLY NET COMPANY, OF MILWAUKEE, WISCONSIN, A CORPORATION OF WISCONSIN

MOP

Application filed June 3, 1929. Serial No. 368,043.

The invention relates to mops and more particularly to the means for adjustably, pivotally connecting the mop head with the handle.

5 Portions of the mop head and the connector are usually made of metal and in order to prevent these metal parts from coming in contact with and marring the surfaces being cleaned, one of the objects of this invention is to provide a pad, preferably of sheepskin with the fleece thereon, which surrounds the end of the connector where it joins the mop frame and is firmly secured thereto, at its ends, preferably by the means for clamping 10 the connector to the mop head. In this connection, it is also an object of the invention to provide the connector with depressions adjacent the clamping bolt so that the head of the bolt and the clamping nut will be de- 15 pressed below the main body of the connector and be protected by the pad and at the same time these depressions act as strengthening corrugations for the jaw portions of the connector.

20 A further object of the invention is to provide a handle connector of one-piece construction in which the rear portion is clamped to the handle by a clamping bolt separate from the bolt that adjustably clamps the 25 jaws to the mop head so that the mop head may be readily and firmly secured to any suitable round handle and special handles need not be furnished. Furthermore, a firm, 30 clamping engagement with the handle is assured and the pivotal adjustment of the head relative to the jaws may be effected 35 without danger of loosening the connector from the handle.

The invention further consists in the several features hereinafter set forth and more particularly defined by claims at the conclusion hereof.

40 In the drawing Fig. 1 is a plan view of a mop embodying the invention, parts of the connector being shown in section and part of the handle being broken away;

45 Fig. 2 is a detail sectional view taken on the broken line 2-2 of Fig. 1;

50 Fig. 3 is a detail sectional view taken on the line 3-3 of Fig. 2;

Fig. 4 is detail sectional view taken on the line 4-4 of Fig. 2.

The invention has been shown applied to the so-called "wire-bound" mops and while this is the preferred construction, the protector and connector hereinafter described are not to be limited to use on this form of mop head, as the invention is applicable to other types of mop heads having pivoted handles.

55 As herein shown, the mop element consists of strands 5 of mop material clamped to a wire frame in known manner, said frame comprising a pair of wires 6 between which the mop strands are initially placed so as to extend outwardly therefrom, after which 60 the wires, held at one end and turned at the other end, are twisted together along their length and in being twisted firmly clamp the 65 mop strands between them.

65 In order to firmly hold the ends of the wire frame together, I prefer to use the coupling 70 of the type shown and described in my co-pending application Serial No. 121,882, filed July 12, 1926. This coupling member 7 consists of a piece of steel or other relatively 75 hard, ductile metal which is turned to provide a conically curved, central portion 8 and end bosses 9, and is provided with a central bore 10 into which the ends of the wire frame are inserted and in which they are firmly secured, as in the aforementioned application, by swaging or upsetting portions 11 of the end bosses 9 so that the bore 10 is distorted and its side walls brought into firm, permanently crimped engagement with 80 the wires.

85 The handle 12 may have a plain or slightly reduced end portion 13 that fits into the cylindrical, split, rear end portion 14 of the sheet metal connector 15 which is formed from a single blank of sheet metal pressed at this end into tubular form, with laterally extending spaced ears 15' at one side provided with openings to receive a clamping bolt 16 provided with a nut 17 for drawing 90 the separated ends of said cylindrical portion together and into firm, clamping engagement with the handle.

95 From this rear end portion 14 the sheet metal blank is shaped to provide a pair of 100

generally semi-cylindrical, resilient clamping jaws 18, having conically curved end portions 19 that are pressed out to fit and tightly engage the conically curved portion 8 of the coupling member 7, and are held in firm engagement therewith by a clamping bolt 20 that extends through openings 21 and 22 in said jaws and preferably has a squared shank portion 23 fitting in the opening 21 and a wing-nut 24 mounted on its threaded end, though an ordinary flat, square or hexagonal nut may be used, said nut being on the top portion of the connector. In order to reinforce the jaws and to prevent the exposed ends of the bolt from sticking out, particularly the head, the lower jaw is pressed to provide a head-receiving depression 25 and the upper jaw is formed to provide a flattened depression 26. Where these depressed portions merge with the side portions of the jaws strengthening ribs 27 are formed. Furthermore, it will be noted that the jaws are not formed as flat, sheet metal projections, but are of curved, channelled construction so that they are very strong and considerable pressure can be imposed upon them by the clamping bolt 20 without danger of breakage or fatigue.

In order to protect the surfaces with which the mop may come in contact from the metal parts of the connector, a pad 28 of sheepskin with the fleece 29 thereon is adapted to extend around the top, front and bottom of the jaws and is secured in place by passing the bolt 20 through openings in said pad adjacent its ends, the lower end being clamped between the washer 30 and the lower jaw, while the upper end is clamped between a washer 31 and the upper jaw, the head and nut of the bolt being thus embedded in and protected by the surrounding fleecy material of the pad, the depressions 25 and 26 also assisting in bringing the parts of the bolt 20 to a position for effective protection by the pad. Other forms of cushioning material may be used but the material sheepskin as above designated is preferred as it may be readily washed.

I desire it to be understood that this invention is not to be limited to any particular form or arrangement of parts except insofar as such limitations are included in the claims.

What I claim as my invention is:

1. A handle connector for mops comprising a single piece of sheet metal having a tubular portion at one end with separable end parts and a pair of resilient jaw portions extending from said tubular portion and separated in a plane coinciding with that of the separable end parts of said tubular portion, said jaw portions being of generally cylindrical shape having their end portions curved to receive a mop pivot and provided with alined openings adjacent their ends and depressed portions surrounding said openings,

an adjustable clamping bolt passing through said alined openings, and means for drawing the separable ends of said tubular portion into clamping engagement with a mop handle.

2. A handle connector for mops comprising a single piece of sheet metal having a tubular portion at one end with separable end parts and a pair of resilient jaw portions extending from said tubular portion and separated in a plane coinciding with that of the separable end parts of said tubular portion, said jaw portions being of generally cylindrical shape having their end portions curved to receive the mop pivot and provided with alined openings adjacent their ends and depressed portions surrounding said openings, a compressible protector pad extending around said jaw portions and having alined openings registering with the openings in the jaw portions, an adjustable clamping bolt passing through said openings in said jaws and pad, and means for drawing the separable ends of said tubular portion into clamping engagement with a mop handle.

In testimony whereof, I affix my signature.

ARTHUR C. KOOTZ.
